CLAIM

The ornamental design for an adjustable P clamp, as shown and described.

DESCRIPTION

FIG. 1 is a top plan view of our design for an adjustable P clamp;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines show portions of the adjustable P clamp that form no part of the claimed design.

Portions of the adjustable P clamp are shown broken away to indicate that those portions have no particular length beyond what is shown.
